UNITED STATES PATENT OFFICE.

HENRY A. JANACEK, OF LA GRANGE, TEXAS.

AUTOMATIC SAFETY DEVICE FOR SPEEDY AND RACING BOATS.

Application filed July 16, 1928. Serial No. 293,080.

The present invention relates to an apparatus for use upon speeding and racing boats and the prime object of the invention resides in the provision of means to cause 5 the boat to be lifted to safety when said boat strikes a high wave.

A still further very important object of the invention resides in the provision of an apparatus of this nature which is normally 10 in an inoperative position when the boat is travelling along on comparatively calm water, but automatically functions as soon as the boat strikes a relatively high wave.

A still further very important object of 15 the invention resides in the provision of an apparatus of this nature which may be easily installed on a boat, is simple in its construction, inexpensive to manufacture, strong and durable, not likely to easily be 20 come out of order, thoroughly efficient and reliable in use and operation and otherwise well adapted to the purpose for which it is designed.

With the above and numerous other objects in view, as will appear as the description proceeds, the invention resides in certain novel features of construction and in the combination and arrangement of parts 25 as will be hereinafter more fully described and claimed.

In the drawings:

Figure 1 is a fragmentary elevation of a boat, showing the bow end thereof with my improved apparatus associated therewith in 30 the normal position.

Figure 2 is a similar view, showing the apparatus adjusted by relatively high waves.

Figure 3 is a top plan view thereof.

Figure 4 is an enlarged detail section, 40 taken substantially on the line 4—4 of Figure 3.

Figure 5 is a section taken substantially on the line 5—5 of Figure 3.

Fig. 6 is a detail view showing the connection between shaft 22 and the elevator plane.

Referring to the drawings in detail, it will be seen that the numeral 5 denotes a boat particularly a relatively speedy boat such as 50 are used for pleasure and racing purposes. A rocker shaft 6 is journaled across the front end of the boat and has cranks 7, on the outer ends thereof extending rearwardly. On the ends of the cranks 7 are floats 8. A crank 9 is on the shaft 6, intermediate its ends within the boat, and is connected

with a link 10, which in turn is connected with a crank 11 on a shaft 12, journaled across the boat above the shaft 6 and a little to the rear thereof. A crank 14 from 60 the shaft 12 is connected with a link 15, which is connected with a crank 16, of a shaft 17. A crank 18 is provided on the shaft 17 and has a link 19 connected therewith for engaging cranks 21, on the shaft 65 22 of elevator planes 23, to the sides of the boat having their rear edges fixed to the shaft 22 and extending forwardly normally in a horizontal position as shown in Figure 1, resting on stops 24. Any number of 70 these elevator planes 23 may be provided to each side of the boat and they are operated all in the same manner through additional links 15, and shafts 17.

From the above detailed description it 75 will be seen that when the boat is going along in relatively calm water as shown in Figure 1, the float cranks 7 rest on stops 26, at which time the planes rest on stops 24. If the boat strikes a relatively high wave 80 as shown in Figure 2, the boat will be raised, the float cranks being limited in their upward movement by stops 27, thereby causing the inclination of the elevator planes 85 upwardly and forwardly from their shafts 22, so as to prevent the boat from cutting through the high waves but causing the boat to rise over the high waves.

It is thought that the construction, operation, utility and advantages of this invention 90 will now be quite apparent to those skilled in this art, without a more detailed description thereof. The present embodiment of the invention has been disclosed in detail, merely for the purposes of exemplification, since in 95 actual practice it attains the features of advantage enumerated as desirable in the statement of the invention and the above description.

It will be apparent that changes in the details of construction, and in the combination and arrangement of parts may be resorted to, without departing from the spirit or scope of the invention as hereinafter claimed or sacrificing any of its advantages.

Having thus described my invention, what I claim as new is:

1. In a boat, a plurality of planes, one or more adjacent to each side of the boat adjacent the bow end thereof, floats to the 110 side of the boat forwardly of the planes, said float and planes spaced above the plane

of displacement, means operatively connecting the floats to the planes so that when the boat strikes the relatively high wave and the floats are raised, such planes will be inclined upwardly with respect to the plane of displacement and forwardly to prevent the boat from diving through the wave, but causing it to ride over the waves.

2. In a boat, a pair of cranks one on each side of the forward end of the boat, means for rockably mounting the cranks at the forward ends, floats at the rear ends of the cranks, means limiting the downward movement of the floats, a plurality of planes, one or more to each side of the boat to the rear of the float, means rockably mounting the rear edges of the plane to the boat, means operatively connecting the planes with the crank, so that when the floats are raised, the cranks are inclined upwardly and forwardly.

3. In a boat, a pair of cranks one on each side of the forward end of the boat, means for rockably mounting the cranks at the forward ends, floats at the rear ends of the cranks, means limiting the downward movement of the floats, a plurality of planes, one or more to each side of the boat to the rear of the float, means rockably mounting the rear edges of the plane to the boat, means operatively connecting the planes with the crank, so that when the floats are raised, the cranks are inclined upwardly and forwardly, means limiting the downward swinging movement of the plane.

4. In a boat, a pair of cranks, one on each side of the forward end of the boat, means for rockably mounting the cranks at the forward ends, floats at the rear ends of the cranks, means limiting the downward movement of the floats, a plurality of planes, one or more to each side of the boat to the rear of the float, means rockably mounting the rear edges of the plane to the boat, means operatively connecting the planes with the crank, so that when the floats are raised, the cranks will incline upwardly and forwardly, means limiting the downward swinging movement of the plane, means limiting the upward swinging movement of the plane.

5. In a boat, a pair of cranks, one on each side of the forward end of the boat, means for rockably mounting the cranks at the forward ends, floats at the rear ends of the cranks, means limiting the downward movement of the floats, a plurality of planes, one or more to each side of the boat to the rear of the float, means rockably mounting the rear edges of the plane to the boat, means operatively connecting the planes with the crank so that when the floats are raised, the cranks will incline upwardly and forwardly, means limiting the downward swinging movement of the plane, means limiting the upward swinging movement of the plane, means limiting the upward swinging of the cranks.

In testimony whereof I affix my signature.

HENRY A. JANACEK.
